(57) **CLAIM**

We claim the ornamental design for a remote control unit for an information terminal device, substantially as shown and described.

DESCRIPTION

FIG. 1 is a top view of a remote control unit for an information terminal device in accordance with the present design.

FIG. 2 is a front view of the remote control unit.

FIG. 3 is a left side view of the remote control unit.

FIG. 4 is a rear view of the remote control unit.

FIG. 5 is a front right perspective view of the remote control unit.

FIG. 6 is a rear right perspective view of the remote control unit; and,

FIG. 7 is a rear right perspective view of the remote control unit.

The broken line showing of the environment is for illustrative purposes only and forms no part of the claimed design.
